PARTING STRIP FOR CONCRETE ROADWAYS AND PAVEMENTS

Edward W. Burgess, Milwaukee, Wis., assignor
to A. O. Smith Corporation, Milwaukee, Wis.,
a corporation of New York

Application February 5, 1934, Serial No. 709,697

11 Claims. (Cl. 94—18)

This invention relates to a parting strip for concrete roads and pavements and is applicable to dividing the pavement on longitudinal and transverse lines where it is desired to prevent irregular cracking of the pavement and to secure and interlock the sections thereof together.

The object of the invention is to provide a combined sheet metal parting strip and tie bar structure which is light in weight and simple to manufacture and which will more efficiently hold and interlock the sections of the paving material together.

Another object is to provide improved means for securing the sections of the sheet metal parting strip end to end.

Another object is to provide improved means for supporting the tie-bar member with respect to the parting strip.

Other objects will appear in connection with the description of the preferred embodiment illustrated in the accompanying drawings.

In the drawings:

Figure 1 is a top plan view of a center strip and tie bar made in accordance with the invention;

Fig. 2 is a side elevation of the center strip without the tie bar;

Fig. 3 is an enlarged transverse vertical section of the center strip on line 3—3 of Fig. 1, showing the means for effecting interlocking of the pavement sections and illustrating the strip and tie bar in position in the pavement;

Fig. 4 is a detail horizontal section through a portion of the center strip showing the means for supporting the tie bar;

Fig. 5 is a transverse section taken on line 5—5 of Fig. 4;

Fig. 6 is an end view of the center strip;

Fig. 7 is a transverse section on line 7—7 of Fig. 2 showing means for receiving the end clips for joining the sections end to end;

Fig. 8 is an end view of one of the clips for securing the sections end to end;

Fig. 9 is a side elevation of a joint between the ends of two center strip sections showing the clip in place;

Fig. 10 is a top plan view showing a joint at the ends of two tie bars and a clip for the same; and

Fig. 11 is a transverse section on line 11—11 of Fig. 10.

The parting strip comprises, in general, a sheet metal strip 1 adapted to be embedded in concrete or other paving material 2 in a vertical position with the top edge of the strip slightly beneath the upper surface of the paving mate-

rial as shown in Fig. 3, and a tie bar 3, which is preferably continuous, extending horizontally in a zig-zag or sinuous formation across the joint to tie the sections of paving material together as shown in Figs. 1 and 3.

The center strip 1 has a vertical upper edge portion 4 and the lower portion of the strip is bent in opposite directions alternately to provide inclined projections 5 and complementary recesses 6 for receiving paving material on opposite sides of the strip. The center strip is preferably formed by a pressing operation in which the metal of the lower portion of the strip is drawn to provide the alternately inclined portions 5.

Alternate inclined projections 5 have a longitudinal slot 7 extending substantially for the full length of each projection for receiving the tie bar 3 and through which the tie bar may be inserted from one side of the strip as illustrated in Fig. 1. The height of the slots 7 in the center strip is dependent upon the desired position of the bar 3 in the pavement, and is preferably approximately midway in the height of the center strip as illustrated in Figs. 2 and 3.

The tie bar 3 is preferably formed from a continuous rod and has notches 8 formed therein at locations where the bar engages the center strip 1.

The metal of the center strip 1 at the ends of the slots 7 is deformed to provide a semi-circular curved groove-like portion 9 for receiving the tie bar 3. On either side of each curved portion 9 is a fold 10 in the opposite direction from the normal plane of the sheet, the portion 9 and folds 10 being adapted to provide a recess for receiving the tie bar and securing it in a horizontal position to prevent its tipping.

The notches 8 in the tie bar are suitably spaced apart to receive the deformed portions 9 and 10 of the center strip and thereby locate the tie bar definitely with respect to the center strip to insure that the dowel extends equidistant on opposite sides of the strip.

The parting strip is preferably formed in definite lengths, such as ten feet and the sections of the strip are joined end to end by means of a clip illustrated in Figs. 7, 8, and 9. For this purpose, the center strip 1 is provided with two longitudinally extending ribs 11 at each end. At a predetermined distance from the end of the strip, the ribs 11 are slit and one portion 12 thereof is bent outwardly to receive the clip 13 as shown in Fig. 7. The clip 13 consists of a sheet metal plate having its upper and lower edge portions curved or beaded on a radius similar to the curva-

ture of the ribs 11 and having projections 14 pressed in its upper and lower edges for locating the clip and preventing its displacement during and after assembly. By employing a clip such 5 as that shown in Figs. 6 to 9, inclusive, the center strips 1 are joined end to end in abutting relation and interlocked from relative transverse and vertical movement. The curved edge portions of the clip 13 stiffen the clip and cooperate with the 10 ribs 11 in interlocking the strips.

The tie bar may be secured at its ends to another section of tie bar by means shown in Figs. 10 and 11. As shown, the tie bars are provided with sufficient length of material to have an 15 overlapping section 15 located at an outer bend of the bar. A U-shaped clip 16 of sheet metal is pressed over the overlapping ends as shown in Figs. 10 and 11, the clip being formed with ribs 17 to hold the same in position.

20 The parting strip may be employed centrally of the roadway with the center strip 1 extending longitudinally of the roadway and the tie bar 3 holding the two sides of the roadway together and assisting in interlocking the same, or the 25 parting strip may be employed at a transverse joint between paving sections with the tie bar holding the sections together end to end and the strip 11 extending transversely across the roadway. In either case, the alternating projections 30 and recesses 5 and 6 form interlocking portions in the sections of paving material which prevent relative vertical movement between the sections at the joint. The tie bar 3 tends to hold the sections together and prevent slippage with respect to the inclined portions 5 of the center 35 strip.

In handling the parting strip, the center strip 1 and tie bar 3 may be shipped separately with several similar parts tied in suitable bundles, and 40 then the parts may be assembled at the time of laying the road. After the parts are assembled, the tie bar 3 tends to stiffen the sheet metal strip 1 and prevent its displacement by reason of the continuous zig-zag shape of the bar 3 and of 45 the notches 8 which tend to hold the strip 1 at the center line of the bar.

Various modifications of the embodiment may be employed within the scope of the invention defined in the accompanying claims.

50 The invention is hereby claimed as follows:

1. A parting strip for pavements and highways comprising a sheet metal strip adapted to be disposed on edge in the paving material and a substantially continuous removable zig-zag tie bar 55 extending laterally through horizontal slots in said strip and into the paving material on either side thereof, said tie bar having means thereon for determining its position relative to said strip and for retaining the bar against displacement 60 laterally relative to said strip, and said means effecting a resilient engagement between the tie bar and said strip.

2. A parting strip for pavements and highways comprising a sheet metal strip adapted to be disposed on edge in the paving material and having lateral projections providing an interlock between the opposite sections of paving material, and a substantially continuous tie bar extending substantially horizontally through said strip and 70 into the paving material on opposite sides thereof, the metal of the strip adjacent the tie bar and extending transversely between opposite projections of the strip being formed to provide means to hold said bar in substantially horizontal position and said tie bar being notched on either side

of said strip to locate the same relative thereto and to effect stiffening of the strip.

3. A parting strip for pavements and highways comprising a sheet metal strip disposed on edge in paving material and having a straight vertical upper edge portion and a lower interlocking portion having the metal in alternate longitudinal areas thereof displaced laterally in opposite directions from the center line of the strip to provide alternate interlocking projections and recesses in the adjacent sections of paving material on opposite sides of the strip and the metal between said alternately displaced areas extending in a direction transverse to the strip, and a tie bar extending through horizontal slots in said strip and adjacent said transversely extending metal between alternate laterally displaced areas and into the paving material on opposite sides thereof, the metal of the strip extending transversely thereof between alternately displaced areas being formed to receive said tie bar and to hold the same relative to said strip.

4. A parting strip for pavements and highways comprising a sheet metal strip disposed on edge in paving material and having a straight vertical upper edge portion and a lower interlocking portion having the metal in alternate longitudinal areas thereof displaced laterally in opposite directions from the center line of the strip to provide alternate interlocking projections and recesses in the adjacent sections of paving material on opposite sides of the strip and the metal between said alternately displaced areas extending in a direction transverse to the strip, and a tie bar extending through said strip adjacent said transversely extending metal between alternate laterally displaced areas and into the paving material on opposite sides thereof, the metal of the strip extending transversely thereof between alternately displaced areas being formed to receive said tie bar and to hold the same relative to said strip, and the tie bar being notched on either side of said strip to prevent displacement of the bar.

5. A parting strip for pavements and highways comprising a sheet metal strip disposed on edge in paving material and having a straight vertical upper edge portion and a lower interlocking portion having the metal in alternate longitudinal areas thereof displaced laterally in opposite directions from the center line of the strip to provide alternate interlocking projections and recesses in the adjacent sections of paving material on opposite sides of the strip, the laterally displaced areas on one side of said strip having longitudinal slots extending substantially for the full length thereof at a predetermined height in said strip, and a continuous sinuous or zig-zag tie bar inserted through said slots from one side of said strip and extending into the paving material substantially equally on opposite sides of said strip.

6. A parting strip for pavements and highways comprising a sheet metal strip disposed on edge in paving material and having a straight vertical upper edge portion and a lower interlocking portion having the metal in alternate longitudinal areas thereof displaced laterally in opposite directions from the center line of the strip to provide alternate interlocking projections and recesses in the adjacent sections of paving material on opposite sides of the strip, the laterally displaced areas on one side of said strip having longitudinal slots extending substantially for the full length thereof at a predetermined height in said strip, and a continuous sinuous or zig-zag

tie bar inserted through said slots from one side of said strip and extending into the paving material substantially equally on opposite sides of said strip, the metal of said strip between said alternate laterally displaced areas extending transversely of the strip and being formed to receive said tie bar and hold the same in a substantially horizontal position.

7. A parting strip for pavements and highways comprising a sheet metal strip disposed on edge in paving material and having a straight vertical upper edge portion and a lower interlocking portion having the metal in alternate longitudinal areas thereof displaced laterally in opposite directions from the center line of the strip to provide alternate interlocking projections and recesses in the adjacent sections of paving material on opposite sides of the strip, the laterally displaced areas on one side of said strip having longitudinal slots extending substantially for the full length thereof at a predetermined height in said strip, and a continuous sinuous or zig-zag tie bar inserted through said slots from one side of said strip and extending into the paving material substantially equally on opposite sides of said strip, the metal of said strip between said alternate laterally displaced areas extending transversely of the strip and being formed to receive said tie bar and hold the same in a substantially horizontal position, and said tie bar having notches therein along the longitudinal center line thereof to secure the same with respect to said strip and to thereby stiffen the latter.

8. In a parting strip for pavements and highways, a plurality of sheet metal center strips formed to provide interlocking projections and recesses between sections of paving material and arranged end to end in upright position in the pavement, said center strips having longitudinally extending beads at the ends thereof, each bead having an opening therein at a distance from the end of the strip, and a sheet metal clip extending across the joint between the strips and having portions extending through said openings in said beads to interlock the strips against relative

transverse and vertical movement, the ends of said strips being free from slots.

9. In a parting strip for pavements and highways, a plurality of sheet metal center strips formed to provide interlocking projections and recesses between sections of paving material and arranged end to end in upright position in the pavement, said center strips being slit longitudinally at a predetermined distance from their ends, and a clip extending across the joint having portions engaging said slits for interlocking the strips against relative transverse and vertical movement the ends of said strips being free from slots.

10. In a parting strip for pavements and highways, a plurality of sheet metal strips arranged end to end and embedded in the paving material for parting sections of the paving material, tie bars extending through said strips and into the paving material on the opposite sides thereof, a tie clip securing the adjacent ends of the strips together and comprising a substantially flat metal plate having its upper and lower longitudinal edges curved or ribbed to stiffen the same, and ribs extending longitudinally of said strips at the adjacent ends thereof and disposed to register with the curved edges of said clip the ends of said strips being free from slots.

11. In a parting strip for pavements and highways, a plurality of sheet metal strips arranged end to end and embedded in the paving material for parting sections of the paving material, tie bars extending through said strips and into the paving material on the opposite sides thereof, a tie clip securing the adjacent ends of each strip together and comprising a substantially flat metal plate having its upper and lower longitudinal edges curved or ribbed to stiffen the same, and ribs extending longitudinally of said strips at the adjacent ends thereof and disposed to register with the curved edges of said clip, said ribs being slit for a portion of their length to receive the edges of said clip.
